UNITED STATES PATENT OFFICE

CHARLES F. DOEBLER, OF NEW YORK, N. Y., ASSIGNOR TO BENJAMIN FRANK, OF NEW YORK, N. Y.

CLIP FOR WRITING TOOLS

Application filed September 22, 1922. Serial No. 589,754.

This invention relates to methods of manufacturing and to clips so manufactured for detachably securing writing tools to the edge of a pocket or other part of a garment, and has for some of its objects to provide clips which are neat, simple, efficient in their gripping action, of long life, and which may be manufactured and assembled at a relatively low cost.

10 Referring to the drawings which illustrate what I now consider a preferred form of the invention:

Fig. 1 is an elevation, partly in section, of a part of a writing tool with one form of my clip attached thereto.

Fig. 2 is an elevation looking in the direction of the arrow A in Fig. 1.

Fig. 3 is an inverted plan view of one of the members shown in Figs. 1 and 2 at an intermediate stage of its manufacture.

Fig. 4 is a view similar to Fig. 3 but illustrating a different member.

Figs. 5 and 6 are views similar to Figs. 3 and 4 respectively but illustrating slightly modified forms of members.

Fig. 7 is a section on the line 7—7 of Figs. 5 and 6.

While my clip may be readily applied to pens, pencils or other writing tools, for the purpose of the present disclosure I shall assume that it is to be applied to a magazine pencil of the general type illustrated in my copending applications, Ser. Nos. 451,467; 452,445; 456,587; 473,445; 481,466 and 590,598.

In Figs. 1 and 2 I have shown a pencil having a barrel or casing 10 which may form the outer casing of the pencil or may be surrounded by an outer casing 11. The clip comprises a tongue 13, secured to the barrel or casing 10, and adapted to engage and grip the edge of a pocket, or other portion of a garment, between said tongue and the body portion of the pencil. A leaf spring 12 relatively fixed with respect to the tongue 13 at its upper end, engages the tongue and biases or aids in biasing the latter toward garment-engaging position, i. e., toward the pencil. The now preferred method of constructing the clip is as follows:

A sheet of material, preferably resilient metal such as nickel-silver, is stamped or punched out in the shape shown in Fig. 3. Here it will be seen that a flat closed loop member 14 is provided, this loop member 55 having an integral tongue 13. The central opening 15 of the loop is shaped to conform with the cross-section of the pencil portion to which the clip is to be attached. The barrel 10, shown in Figs. 1 and 2 is cylindrical so that the opening 15 is shown as circular. Preferably the opening 15 is made of such size as to form a driving fit with the barrel or casing 10 when the member 14 is driven or forced over the pencil, in order to 60 securely and rigidly hold the parts in assembled position. Obviously other forms of attaching means between the clip and pencil may be resorted to. The member 14 is shown with a notch 16 for a purpose hereinafter 65 appearing. The free end of the tongue 13 is preferably dished as indicated in Figs. 1 and 2 so as to present a convex surface toward the pencil for engaging the garment. The tongue 13 is bent in a general downward direction with respect to the loop 14 and is 70 preferably curved to the shape illustrated in Figs. 1, 2 and 3.

The leaf spring 12 is shown integrally secured to a flat-closed loop member 14^a having an opening 15^a. The manufacture and design of the structure shown in Fig. 4 is substantially the same as that shown in Fig. 3, except that the leaf 12 is shown slightly shorter than the tongue 13 and is not dished at 75 its free end, and except further that the member 14^a is provided with a struck-up lug 16^a instead of a notch 16. The member 14^a and its leaf 12 are constructed of resilient sheet material, preferably resilient metal, such as 80 nickel-silver.

The parts may be assembled as follows. The member 14 is forced or driven down over the casing 10 to the desired position (see Fig. 1). By virtue of the driving fit the parts 10 and 14 will be rigidly and securely connected. The member 14^a is then forced or driven down over the casing 10 in such position that the lug 16^a will enter the notch 16 and so that the parts 14, 14^a and 12, 13 will engage each other 100

as indicated in Figs. 1 and 2. The driving fit between each of the elements 14, 14^a and the casing 10 will hold the parts securely in assembled position and the co-action of the lug 16^a and notch 16 will prevent relative rotation of the members 14, 14^a and insure that the elements 12, 13 align and stay in alignment. Obviously the driving fit connection between the casing 10 and the clip may be replaced or 10 supplemented by other connections such as soldered joints, screw connections, etc.

It will be noted that the tongue 13 and leaf 12 constitute laminæ to form a laminated cantilever spring tongue. The lamina 12 is 15 relatively slidable with respect to the lamina 13 except at the upper ends of the same. A strong durable spring tongue is thereby provided which will effectively engage and grip the pocket, or other portion of a garment, 20 between said tongue and the body of the pencil.

The clip is susceptible to modification in various respects without departing from the scope of the invention as defined in the following claims. For example, if the cross-section of that portion of the pencil, at which the clip is to be applied, is polygonal, the openings 15 and 15^a would be correspondingly shaped. In this case the notch 16 and lug 30 16^a may be omitted. Thus in Figs. 5 and 6 I have shown the design of the parts when adapted to be applied to a pencil whose cross-section is hexagonal at the attaching portion.

Preferably the tongue 13 is transversely concaved as shown in Fig. 7 to stiffen the same, the convex portion or bridge lying toward the tool 11 when the parts are assembled. It will also be noted that the leaf or tongue 12 lies in the groove or concavity of the tongue 13 (see Fig. 7). Obviously the feature shown in Fig. 7 may be embodied in either or both of the forms of clips illustrated in Figs. 1 to 4 or 5 and 6.

What I claim is:

1. The combination with a tubular body, of a clip comprising a tongue and a reinforcing member in engagement therewith, one end of said reinforcing member being secured to said tubular body and the other end being free to slide on said tongue, and means encircling said tubular body for securing said tongue thereto.

2. The combination with a tubular body, of a clip comprising a resilient tongue and a reinforcing member in slidable engagement therewith, means for securing said tongue to said tubular body, and means encircling said tubular body for securing said reinforcing member thereto.

3. A garment-gripping clip for writing tools comprising in combination, a flat closed loop member through which the tool is adapted to extend, and a garment-engaging tongue projecting from one side of said mem-

ber and bent downwardly with respect thereto.

4. A garment-gripping clip for writing tools comprising in combination, a flat closed loop member through which the tool is adapted to extend, a garment-engaging tongue projecting from one side of said member and bent downwardly with respect thereto, a second flat closed loop member adapted to superimpose upon said first named member and through which the tool is adapted to extend, a leaf spring portion projecting from one side of said second member and bent downwardly with respect thereto to engage said tongue substantially throughout the length of the latter.

5. The invention defined in claim 4 in which one of the loop members is provided with a lug which extends into a notch in the other loop member to prevent relative rotation of said members.

6. The invention defined in claim 5 in which means are provided for preventing relative rotation of the two loop members.

7. The invention defined in claim 5 in which means are provided for preventing relative lateral motion of the tongue and the leaf spring.

8. The invention defined in claim 5 in which the tongue and the leaf spring project tangentially to the planes of the respective loops.

9. The combination with a tubular body of a clip comprising a tongue and a resilient reinforcing member in slidable engagement therewith, means encircling said tubular body for securing said tongue thereto, and independent means encircling said tubular body for securing said reinforcing member thereto.

10. The combination with a tubular body, of a clip comprising a tongue and a reinforcing member in resilient engagement therewith, means encircling said tubular body for securing said clip thereto, and means for preventing relative lateral motion of said tongue and said reinforcing member.

11. The combination with a tubular body, of a clip comprising a tongue and a reinforcing member in resilient engagement therewith, means encircling said tubular body for securing said tongue thereto, other means encircling said tubular body for securing said reinforcing member thereto, and means for preventing relative rotation of said two encircling means.

12. A clip comprising a flat loop adapted to be fitted unto a tubular body, and a tongue integral with said loop projecting therefrom tangentially to the plane thereof and bent downwardly with respect thereto.

13. A clip comprising a flat loop adapted to be fitted unto a tubular body, a tongue integral with said loop projecting therefrom tangentially to the plane thereof and bent downwardly with respect thereto, and a rein-

forcing member in resilient engagement with said tongue.

14. A clip comprising two superimposed flat loops adapted to be fitted unto a tubular body, a tongue projecting from each loop tangentially to the plane thereof and bent downwardly with respect thereto, said two tongues being also superimposed, and means for preventing relative lateral motion of said tongues.

10 15. A clip comprising a flat loop adapted to be fitted unto a tubular body, a tongue integral with said loop projecting therefrom tangentially to the plane thereof, and a corrugation in said tongue substantially the entire length thereof, the convex side of said corrugation being towards said loop.

20 16. A clip comprising two superimposed flat loops adapted to be fitted unto a tubular body, a tongue for each loop integral therewith projecting therefrom tangentially to the plane thereof and bent downwardly with respect thereto, and a corrugation in one of said tongues substantially the entire length thereof, the other tongue being disposed within said corrugation.

In testimony whereof I hereto affix my signature.

CHARLES F. DOEBLER.
